UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

MACHINE FOR WRAPPING TIRE TAPE OR THE LIKE.

Application filed January 26, 1924. Serial No. 688,690.

This invention has to do with a machine for placing tin foil covers about rolls of frictional fabric or tire tape, although its use is not so restricted, but may be extended as found practicable. Heretofore, to my knowledge, the application of this cover has been entirely by hand, and it is the purpose of the present invention to devise a machine for displacing the hand operation. 10 The machine has particularly to do with the folding of the edges of the cover over the sides of the roll. The machine operates more rapidly and satisfactorily than the hand operation.

15 In the drawings there is shown one form of the invention, it being understood that other forms may be adopted within the spirit and scope of the appended claims.

In the drawings:

20 Figure 1 is a side elevation of the machine;

Figure 2 is an end view;

Figure 3 is a roll of tire tape, uncovered; and

25 Figure 4 is a covered roll such as produced by the machine.

The machine comprises a table or platform 1, the upper surface of which is removed along a given line to accommodate a belt 2 which is supported on pulleys 3 and 4 so that its upper run is substantially flush with the top of the table. The belt is driven at suitable speed from a motor 5, having a reduction gearing 6 and clutch 7 controlled 30 by a foot lever 8. A sprocket 9 connected to the clutch and the pulley 4 serves to drive the latter.

At the sides of the belt are arranged upright posts 10 on which is loosely mounted 40 and guided an inverted channel 11, which may be weighted if desired and provided at one end with guiding flanges 12 which may be spring pressed as shown at 12a. Adjustable collars 13 are supported upon the posts 45 to limit the downward movement of the channel, this provision being necessary to enable the machine to operate upon rolls of different sizes.

Parallel to the belt are folding or crimping bars or rolls 14. These are long rollers spaced apart a distance slightly greater than the width of the roll and are round bars tapered at the front end as at 15. The front end of each bar is adjustably supported in a 50 standard 16 near the front end of the belt

and the rear end of the bar is pivotally supported in a short standard 17 near the end of the belt. As shown, the bar is inclined relative to the belt so that at the entrance to the machine it will be located near the outer periphery of the tape roll. In this manner, the projecting edges of the tin foil are attached at the edge of the roll and gradually shaped down over the surface of the roll as the roll is moved forwardly by the belt. 60

At the far end of the table the roll of tape with the tin foil roughly shaped about it, is passed into a chute 18, at the lower end of which are located two pressing or finishing rolls 19. These rolls are journaled on the upper ends of levers 20 which are pivoted at 21 on an apron 22 in front of the machine. The rolls are rotated from the shaft of the pulley 4 by a sprocket chain 23 which drives the sprocket 24, which is in turn connected to 70 a bevel gear 25. From the gear 25 the rolls are driven through the gearing indicated at 26 in Figure 2. The levers 20 are forced apart at their lower ends, which presses the rolls 19 together by a link 27 on the ends of 75 which are mounted springs 28 which exert the yielding pressure required.

In the operation of the machine, the operative rolls the tire tape in a layer of tin foil so that the edges of the foil project outwardly of the roll. He then feeds the roll onto the belt and beneath the presser bar 11. The belt rolls the tire tape forwardly and the side rolls 14 give it a preliminary shaping against the side of the roll. As it drops through the chute 18, the rolls 19 give the tin foil a final pressing. 80

It is obvious that the invention is not limited to strict conformance with the showing made herein, but may be varied and modified as required; nor is it limited to wrapping tire tape, or to the use of tin foil, and it may be more widely adapted if desired. An unwrapped roll of tape is shown in Figure 3 and a covered roll in Figure 4. 100

What is claimed is:

1. In a machine for applying a wrapper to cylindrical objects, in combination, a belt conveyor, a yieldable pressure bar provided with guiding flanges, said bar being mounted above said conveyor and spaced therefrom to guide and roll the object, a pair of inclined folding rollers at the sides of the conveyor belt for acting upon the edges of the wrapper to fold it progressively from the 105 110

periphery to the center of the object, a chute for receiving the object from the conveyor, and yieldable pressure rollers arranged transversely of the chute to compress the 5 folds of the wrapper onto the side faces of the object.

2. In a machine for applying a wrapper to cylindrical objects, in combination, a belt conveyor, a yieldable pressure bar, said bar and said conveyor being spaced apart to receive an object therebetween and adapted to cooperate with the object to roll the same, folding bars on opposite sides of the conveyor inclined downwardly from the entering 10 end toward the delivering end of the conveyor adapted to engage and fold the wrapper progressively from the periphery toward the center of objects passing therebetween, and a chute arranged to receive the objects from the conveyor, and pressure rollers to compress the folds of the wrapper against the 15 faces of the object.

3. In a machine for applying a wrapper to cylindrical objects, in combination, a belt conveyor, a yieldable pressure bar, said bar

and said conveyor being spaced apart to receive an object therebetween and adapted to cooperate with the object to roll the same, folding bars on opposite sides of the conveyor inclined downwardly from the entering 20 end toward the delivering end of the conveyor adapted to engage and fold the wrapper progressively from the periphery toward the center of objects passing therebetween, and a chute arranged to receive the 25 objects from the conveyor.

4. In a machine for applying a wrapper to cylindrical objects, in combination, a belt conveyor, a yieldable pressure bar, said bar and said conveyor being spaced apart to receive an object therebetween and adapted to cooperate with the object to roll the same, and folding bars on opposite sides of the conveyor inclined downwardly from the entering 25 end toward the delivering end of the conveyor adapted to engage and fold the wrapper progressively from the periphery toward the center of objects passing therebetween.

HORACE D. STEVENS.
